(57) **CLAIM**

The ornamental design for a meter, as shown and described.

DESCRIPTION

FIG. 1 is a front perspective view of an exterior of a meter showing our design;

FIG. 2 is a front view thereof;

FIG. 3 back view, opposite the front view thereof;

FIG. 4 is a first side view thereof;

FIG. 5 is second side view thereof, opposite that shown in FIG. 4;

FIG. 6 is a top view of the meter; and,

FIG. 7 is a bottom view thereof.

The broken lines shown in the figures depict environment that form no part of the claimed design.
